READILY CLOSABLE AND REOPENABLE PLASTIC BAG

James C. Kratzer, Riverside, Conn., and Peter Wilton, Plainfield, N.J., assignors to Union Carbide Corporation, a corporation of New Jersey

Filed Mar. 26, 1963, Ser. No. 268,117

3 Claims. (Cl. 229—80)

The invention relates to a readily closable and reopenable bag, and particularly refers to a plastic bag suitable for protecting sandwiches and other foods.

Plastic bags provide a very convenient way to protect or store sandwiches, foods in general, or other substances found in the home. The bags are relatively inexpensive, and are usually transparent for easy viewing of the contents, sanitary, and sufficiently durable for home and other light uses. One drawback of prior art bag constructions, however, is the lack of a convenient way to close the bags.

Many bags presently commercially available, for example, include no closure means. As a result, the open end of the bag must be rolled or folded over to close the bag, and the roll or fold must then be kept in place by adhesive tape or a rubber band placed around the bag. With larger size bags, coated wires or strings are frequently packaged with the bags to provide a means for tying the open end of the bag in a closed position. Separate components such as the above, however, are frequently misplaced, and the bags remain without an effective closure means.

The primary object of the invention, therefore, is to provide a readily closable and reopenable bag.

In the drawings:

FIG. 1 is a perspective view of a bag made in accordance with the invention and having a bread slice therein;

FIG. 2 is a schematic view of a cross-section of the bag shown in FIG. 1; and

FIG. 3 is a schematic view of a cross-section of the bag shown in FIG. 1 with its open end closed.

Broadly, the above object is achieved by a bag made of a plastic material and having a flap extending from one wall of the bag at the open end, the bag having a substantially non-volatile, high viscosity liquid on the inside surface of the flap, the outside surface of the bag wall opposite the side of the flap, or both. This bag construction may be closed merely by folding the flap over the open end and against the opposite wall. The liquid existing between the flap and the opposite wall in this closed position causes the flap to cling to the wall with sufficient force to withstand ordinary handling without loosening. On the other hand, the bag may be readily opened by pulling up one corner of the flap from the opposite wall until the flap loosens from the opposite corner.

Referring now to the drawing, FIG. 1 is a perspective view of a bag made in accordance with the invention containing a bread slice 9. The bag comprises a first wall 10 and a second wall 12 with an open end between the two and a flap 14 extending from the first wall 10. The walls 10 and 12 may be heat-sealed or glued together at their edges, or the walls may be made by heat-sealing or gluing a tubular piece of material together at one end. The bag may also have third and fourth walls connecting the first and second walls 10 and 12 if a bag capable of containing larger amounts is desired. The third and fourth walls may be made to fold as in an ordinary paper bag construction to facilitate storage.

The flap 14 may be an integral extension of the first wall 10, or may be attached to the first wall 10 by any suitable means, such as adhesives or heat-sealing. The flap 14 is preferably wide enough to cover the open end of the bag substantially completely when folded over, i.e.,

2

in general substantially the same width as the first wall 10, but a narrower flap may be employed if the material to be contained will not fall out or dry out too rapidly because of only a partially closed open end.

5 The bag may be made of any plastic material, preferably having substantially non-clinging characteristics, such as vinylidene chloride polymers, ethylene polymers, propylene polymers, styrene polymers, ester polymers, and vinyl chloride polymers, the term polymer including homopolymers and copolymers with at least one additional monomer. Such materials may of course include plasticizers, bodying agents, extenders, modifiers, and the like. Materials which tend to cling together to a substantial degree are not preferred since the bag walls will 15 stick together and the ease with which an article may be inserted in the bag will be reduced thereby. Polyethylene is preferred as the plastic material, but unplasticized polyvinylidene chloride, polystyrene, polypropylene, polybutylene, and polyvinyl chloride may also be considered 20 as preferred materials.

As shown schematically in FIGS. 2 and 3, a substantially non-volatile, high viscosity liquid 16 is coated on the inside surface of the flap 14, the outside surface of the second wall 12, or both to cause the flap 14 to cling to 25 the second wall 12 when folded over and against this wall. Preferably, the only parts of the bag which are coated with the liquid 16 are the surfaces which exist between the flap 14 and the second wall 12 when the flap is folded over. Other outside surfaces may be coated, but no 30 purposes in accord with the invention are attained while too much coating tends to cause problems in packaging. In addition, a small area (indicated at 20) at the top of the second wall 12 and a similar area at the bottom of the flap 14 (indicated at 22) are preferably left uncoated with 35 the liquid 16 in order to keep the liquid 16 away from direct contact with any materials contained in the bag. Areas at least about $\frac{1}{4}$ inch wide but not so wide as to prevent good clinging have been found to be sufficient. Areas between about $\frac{1}{4}$ inch and $\frac{1}{2}$ inch wide are preferred.

The substantially non-volatile, high viscosity liquid is 40 preferably selected from those liquids and mixtures thereof which are substantially inert, i.e., not deleterious, to the plastic bag material and which have a vapor pressure at 25°C. between about 0.01 and about 10 millimeters of mercury and a viscosity at 25°C. between about 100 and about 250 centipoises. Preferred cling agents as components of these liquids include mineral oils; silicone oils; fatty acids; esters of fatty acids, both saturated and unsaturated, with polyhydric alcohols; aliphatic polyhydric alcohols; aliphatic monohydric alcohols; epoxidized oils such as epoxidized vegetable oils; and mixtures thereof. Epoxidized soy bean oil, glycerol monostearate, glycerol monooleate, and commercial mineral oil may be mentioned as examples of the preferred materials with the glycerol monooleate the most preferred. These materials 45 may of course include liquefying extenders, bodying agents, modifiers, plasticizers, and the like to impart a vapor pressure and viscosity to the cling agent within the desired ranges recited above. Liquefying extenders comprise such materials as water and alcohols, for example, methanol, ethanol, propyl alcohol, butyl alcohol, ethylene glycol, propylene glycol, and glycerol.

50 A liquid comprising glycerol monooleate in a major portion as a cling agent and about 11 percent by weight propylene glycol as a liquefying extender has been found to be the most satisfactory. This liquid has the following characteristics:

70 Clear amber liquid

Viscosity—about 150 centipoises at 25°C.

Specific gravity—about 0.96 at 25° C.
 Moisture content—not more than 0.5% by weight
 Total monoglycerides (α and β forms) about 54 to about 59% by weight
 Free fatty acid (as oleic)—not more than 0.5%
 Remainder—principally, diglycerides and propylene glycol with less than 1 percent by weight preservatives

The liquid 16 may be coated on the bag in an undiluted form, or may be first diluted in a volatile solvent, such as ethanol, methanol, water, and the like, and then coated on the bag. Preferred coating methods include spraying, roller or brush coating, and doctor blading, but any suitable technique, such as compounding the liquid 16 with the plastic material before making the plastic film or bag, may be employed. If the liquid 16 is compounded with the plastic material, it will migrate to the surface of the plastic to form a liquid film thereon. Undiluted liquid has been successfully used in the coating methods as well as 2, 2.5, 4, 5, 10, and 20 percent concentrations by volume in ethanol. In any event, a thin film of the liquid 16 must be present on the bag at the appropriate places. The thin film must be thick enough to achieve sufficient cling but preferably not so thick as to appear unsightly or to feel undesirably sticky to one who handles the bag. Between about 50 and about 800 milligrams of the liquid 16 per square meter of plastic material has been found to be satisfactory.

Several bags made in accordance with the invention have been tested, with glycerol monooleate as the liquid cling agent in most cases. The bags were of a size suitable for sandwiches, and when the flap was folded over to close the bag, the closure was sufficiently positive and strong to permit liberal handling without causing the bag to open. In fact, the bag with its contents was vigorously shaken without a loosening of the flap from the bag wall. The bag can be opened, however, merely by pulling up a corner of the flap and continuing the action until the flap is loose. In addition, the bag may be closed and opened a number of times without harming the bag or the cling agent. Thus, the invention provides a readily closable and reopenable bag, and eliminates the need for separate closure means for plastic bags or inconvenient adhesives which permanently bond one material to another.

The term liquid as used herein means a material or mixture of materials which will by its inherent nature without the aid of solvents flow at 25° C. but which does not diffuse and fill any container virtually uniformly in which it is put, as a gas will do. The term "substantially non-volatile, high viscosity liquid" as used herein means a liquid which evaporates very slowly at room temperatures

and pressures, thus being relatively permanent when exposed under ordinary conditions, and which resists flow to a greater extent than materials such as water, ethylene glycol, and 98 percent sulfuric acid, which have viscosities less than about 25 centipoises at 25° C. In general, this term means a liquid having a vapor pressure at 25° C. below about 20 millimeters of mercury and a viscosity at 25° C. above about 25 centipoises.

The liquid cling agent in accordance with the invention is to be contrasted with adhesive materials which must be wet with water or other solvents before they can be used as an adhesive and which almost always produce a permanent bond after drying again, i.e., a bond which can be broken only with great difficulty and usually by harming the bonded materials or the adhesive.

What is claimed is:

1. A readily closable and reopenable bag made of a flexible plastic material; said bag having a first wall and opposite said first wall a second wall, an open end between said first and second walls, and a flap extending from said first wall for folding over said open end and against said second wall, thereby closing said open end; and said bag having a thin film thereon, on at least one surface which exists between said flap and said second wall when said flap is folded over, consisting essentially of from 54 to about 59% by weight of a monoglyceride selected from the group consisting of glycerol monostearate and glycerol monooleate, not more than 0.5% by weight oleic acid, and the remainder diglycerides and propylene glycol; said film causing said flap to cling to said second wall when said flap is folded over.
2. The bag as defined in claim 1 wherein said liquid has a vapor pressure at 25° C. between about 0.01 and about 10 millimeters of mercury and a viscosity at 25° C. between about 100 and about 250 centipoises.
3. The bag as defined in claim 1 wherein the monoglyceride is glycerol monooleate.
